CLAIM

The ornamental design for a contour plotter for eyewear, as shown and described.

DESCRIPTION

FIG. 1 is a perspective view of a contour plotter for eyewear showing my new design, shown with the cover in an open condition;

FIG. 2 is a perspective view, shown with the cover in a closed condition;

FIG. 3 is a top plan view of FIG. 1 thereof;

FIG. 4 is a bottom plan view;

FIG. 5 is a front elevational view;

FIG. 6 is a rear elevational view;

FIG. 7 is a left side elevational view; and,

FIG. 8 is a right side elevational view thereof.

FIGS. 1 and 2 has been drawn on a slightly enlarged scale with respect to FIGS. 3-8.

FIG. 1

FIG. 2

FIG. 3

FIG. 4

FIG. 5
